UNITED STATES PATENT OFFICE.

JOHN T. FINLEY, JR., OF ATLANTA, GEORGIA, ASSIGNOR OF ONE-THIRD TO JOHN T. FINLEY, SR., AND ONE-THIRD TO WILLIAM M. JENNINGS, BOTH OF ATLANTA, GEORGIA.

RAIL-JOINT.

1,150,108.

Specification of Letters Patent. Patented Aug. 17, 1915.

Application filed January 26, 1914. Serial No. 814,569.

To all whom it may concern:

Be it known that I, JOHN T. FINLEY, Jr., a citizen of the United States, residing at Atlanta, in the county of Fulton and State 5 of Georgia, have invented certain new and useful Improvements in Rail-Joints; and I do hereby declare the following to be a full, clear, and exact description of the invention, such as will enable others skilled in the 10 art to which it appertains to make and use the same.

This invention relates to new and useful improvements in rail joints and has for its principal object the provision of a rail joint 15 which will firmly clamp the ends of a pair of abutting rails in place and prevent the same from becoming out of alinement.

Another object of the invention is to provide a rail joint wherein the usual wood 20 filler block is eliminated and a metallic filler plate is substituted therefor.

A further object of the invention is the provision of a rail joint wherein the backing off of the nut from the bolt used there- 25 in is eliminated and a permanent joint is thus formed which will do away with the danger usually accompanying the use of the old type of joint.

A still further object of the invention is 30 the provision of a rail joint which will materially reduce the amount of noise caused by the travel of traffic thereover and which will prevent any vertical or lateral movement of the ends of the rails.

With the above and other objects in view 35 the invention consists in the novel combination and arrangement of parts which will be more fully set forth in the following specification and accompanying drawings, 40 in which—

Figure 1 is a perspective view of a rail joint constructed in accordance with this invention showing the ends of a pair of abutting rails in place, Fig. 2 is a transverse sectional view showing the same before being tightened, Fig. 3 is a transverse sectional view similar to Fig. 2 showing the same after being tightened, Fig. 4 is a fragmental perspective view of the angle shoe, Fig. 5 is a 45 transverse sectional view of the angle shoe, and Fig. 6 is a detail perspective view of the filler plate.

Referring now to the drawings by characters of reference, the numerals 1 and 2 50 designate the ends of abutting rails, each of

which comprises the head 3, web 4, and flange 5.

The numeral 6 indicates a railroad tie upon which the ends of the abutting rails rest.

The rail joint which is formed of the several coöperating members is designated generally by the numeral 7 and comprises essentially the angle plates 8 and 9 and the resilient element designated by the numeral 10. 65 Each of the above mentioned elements will be described in detail as the description proceeds. Passing now to the description of the angle plate 8 the same comprises the body portion 11, having formed integral therewith at each side the beads 12 and 13 respectively. A lateral extension 14 is formed integral with the body portion 11 and extends angularly with relation thereto to form the flange engaging portion by 70 means of which the rail flange is held firmly in place. The free edge of this extension 14 is provided with the downturned flange 15 as clearly illustrated in Figs. 2 and 3. It will be apparent, as illustrated in Fig. 3, 80 when the several elements of the rail joint are tightened that the angle plate 8 will act, as a support for the head of the rail and prevent the same from becoming twisted.

The angle plate which is designated generally by the numeral 9, comprises a body portion 16, having formed at each of its lateral extremities the longitudinally extending ribs or beads 17 and 18, respectively, which correspond in every feature to 90 the ribs 12 and 13 formed on the body portion 11 of the angle plate 8. A flange engaging extension 19 is formed integral with the lower extremity of the body portion 16 and is adapted to engage the flange of the 95 rail when the device is in use.

It will be clearly seen that when the angle plate 9 is in place and the device firmly clamped together as illustrated in Fig. 3 that the body portion 16 will act as a support for the head of the rail on the side opposite the body portion 11 and prevent the said head from twisting.

Having described the supporting elements for the ends of the rails it now remains to describe the resilient element above referred to by the numeral 10, which comprises a suitable plate 20, which is formed of spring steel and is provided with the rounded edges 21 and 22. This plate 20 is preferably seg- 110

mental in cross section as clearly shown in Fig. 6 to form a spring or resilient element which will effectively take the place of the usual wood filler block when the device is in use. This plate 20 is provided near its ends with suitable bolt receiving apertures 23 which are of such size as to eliminate any danger of interference from the bolt when the device is being tightened.

10 Coöperating with the plate 20 and interposed between the plate and the nut is preferably provided the upstanding portion 24 which is formed integral with the base member 25 as clearly shown at 26 and is 15 provided with suitable apertures 27 through which the bolts 28 are adapted to extend. The portion 24 preferably extends at an angle slightly off the perpendicular to the base portion as clearly shown in Figs. 4 and 20 5. The base 25 is preferably provided at its lateral extremity opposite the upstanding portion 24 with a suitable beveled portion 29 to assist in placing the plates in position. The base portion 25 is preferably provided 25 with the recesses 30 in its beveled edge as clearly illustrated in Fig. 4 to receive spikes by means of which the device is securely held in place on the tie.

In use it will be apparent that the angle 30 plates are first placed in position with relation to the rails and the bolt passed therethrough, the plate 20 is then slipped in place and the upstanding portion 24 placed thereover with the extension 25 lying beneath the 35 flanges of the rail. Upon placing the nut on the bolts and tightening the same it will be

evident that the plate 20 will be flattened as illustrated in Fig. 3 and the upstanding portion 24 will assume a substantially perpendicular position with regard to the base member 25. Owing to the resilient action of the member 24 and the plate 20 it will be apparent that the bolts and nuts will remain in proper relation and the nuts will be prevented from backing off due to the action 45 of traffic over the road.

While in the foregoing I have shown and described the preferred embodiment of the invention it is to be understood that I may make such changes in the combination and arrangement of parts as fall within the scope of the appended claim.

What is claimed is:—

The combination with the abutting ends of a pair of rails, an angle plate, a fish plate, an angle shoe incasing the rail bases and the fish plate, bolts extending through the angle plate, rails, fish plate, and angle shoe to hold the whole in locked position, of a resilient and transversely curved metallic 55 filler plate interposed between the angle shoe and the fish plate, said filler plate being flattened upon tightening the bolts and thereby forcing the whole into intimate 60 engagement.

In testimony whereof I affix my signature in presence of two witnesses.

JOHN T. FINLEY, JR.
